CONSOLE FOR READING IDENTIFYING IMPRINTS ON DOCUMENTS

Robert B. Boyer, 39 Buckley Ave., West Warwick, R.I.
02893, and Samuel F. Marsocci, Jackpine Road,
Coventry R. I. 02816

Filed Apr. 8, 1970, Ser. No. 22,323

Term of patent 14 years

Int. Cl. D14—02

U.S. Cl. D26—5

FIG. 1 is a perspective view showing a console for reading identifying imprints on documents embodying our new design;

FIG. 2 is a front elevational view thereof;

FIG. 3 is a side elevational view thereof;

FIG. 4 is a rear elevational view thereof; and

FIG. 5 is a bottom plan view thereof.

We claim:

The ornamental design for a console for reading identifying imprints on documents, substantially as shown.
